FURNACE CONTROL

Anker E. Krogh, Philadelphia, Pa., assignor to The
Brown Instrument Company, Philadelphia, Pa.,
a corporation of Pennsylvania

Application October 7, 1937, Serial No. 167,718

9 Claims. (Cl. 236—15)

The general object of the present invention is to provide an improved system for controlling temperature conditions in annealing furnaces of the intermittent type, and in other heat treating furnaces in which it is desirable to make the heating of the furnace dependent both upon the temperature of the work and the temperature of the furnace, so that the work may be brought up to, and maintained at a predetermined soaking 5 temperature, without unnecessary waste of time in completing the heat treating operation, while at the same time avoiding risk of injuriously overheating the work or furnace.

The present invention is particularly adapted 15 for, though not limited to, use in controlling the work and furnace temperatures in a heat treating furnace of the bell, or removable dome, type, and is characterized in particular, by the comparative simplicity of the control apparatus required for regulation of the furnace heating effect 20 in response to separately measured work and furnace temperatures.

In accordance with the present invention a 25 single measuring and control instrument is employed to separately measure work and furnace temperatures and to effect control actions in accordance with the measurements.

In the preferred practical form of the present 30 invention, a single controlling potentiometer instrument in association with a periodically operating switch mechanism, measures and records the temperatures to which one furnace and two work temperature thermocouples are subjected, 35 successively at regular intervals, and, suitably adjusts the instrument control contact of a so-called "proportioning" control system. The latter includes a reversible relay motor which is automatically operated to make the rate of heat 40 supply to the furnace under normal operating conditions, that required to maintain an approximately constant predetermined controlling work temperature, except that the furnace temperature, when it exceeds a somewhat higher predetermined temperature, causes the motor to 45 operate in the direction to reduce the rate of heat supply to the furnace.

The various features of novelty which characterize the present invention are pointed out with 50 particularity in the claims annexed to, and forming a part of this specification. For a better understanding of the invention, however, its advantages and specific objects attained with its use, reference should be had to the accompanying drawing and descriptive matter in which I

have diagrammatically illustrated and described a preferred embodiment of the invention.

The one figure of the drawing is a diagrammatic representation of a bell type furnace, and means for controlling the heat supply to the 5 furnace in response to work and furnace temperatures.

In the embodiment of the invention diagrammatically illustrated by way of example, A represents the bell or dome of a furnace of well-known type, comprising a hearth or furnace base B upon which the bell A is seated during the heating operation, and from which it is removed for the removal of the treated work and the introduction of work to be treated. The bell A 15 as ordinarily constructed comprises a metal shell and a refractory lining A'. Ordinarily, and as shown, the roof of the bell A carries a bail or eye A² for engagement by the hook of a crane (not shown) employed to lift the bell off, and 20 replace it on the base B. The work C in the furnace to be annealed or otherwise heat treated, as conventionally illustrated, consists of a pile of metal plates stacked up on the base B. As shown 25 the work C is enclosed by an inner bell, hood, or work cover of metal, smaller than and spaced away from the side and roof walls of the bell A. The hood D rests on the base B. Sealing means D' are provided to prevent gas leakage between 30 the space enclosed by the inner hood or cover D, 30 and the space between the bell A and hood D.

The furnace conventionally illustrated in the drawing, is of the well-known, so called "radiant tube" type, in which the furnace is heated by radiation from a plurality of metal tubes E, 35 each comprising a vertical portion at the inner side and adjacent the vertical wall of the hood A, and having upper and lower end portions extending horizontally through said wall. Each of the tubes E serves as a combustion chamber receiving a mixture of fuel gas and air for combustion at its lower end, from a supply manifold F at a rate regulated, as diagrammatically illustrated, by the adjustment of a supply valve G. Each tube discharges products of combustion at 40 its upper end. As shown sealing means A³ are provided for sealing the joint between the lower edge of the hood A and the base B, and other sealing means A⁴ are provided to prevent leakage through the openings in the vertical wall of the 45 bell A through which the upper horizontal portions of the tubes E extend, those openings being larger in cross section than the tubes, to accommodate the relative expansion of the tubes E and bell A.

In the drawing H and I are thermocouples responsive to the temperatures of the work adjacent its top and bottom, respectively, and J is a thermocouple responsive to the furnace or tube 5 temperature. As shown the thermocouple J has its hot junction closely adjacent the outer side of the vertical portion of one of the heating tubes E.

A switch mechanism KL is provided to connect 10 the terminals of the three thermocouples in regular succession to conductors 1 and 2 running to the measuring terminals of a temperature measuring and control instrument M. As diagrammatically shown, the switch mechanism KL 15 comprises a circular series of similar arc shaped contacts H', I' and J', a second series of similar arc shaped contacts H², I² and J² and switch arms K and L carried by a constantly rotating shaft N. The thermocouple H has one terminal 20 connected to the contact H', and its second terminal connected to the contact H², and the two contact arms K and L are so disposed relative to the two sets of contacts, that the arms K and L are simultaneously in engagement with the 25 contacts H' and H², respectively, for a suitable fraction, ordinarily little less than one-third, of the time required for each revolution of the shaft N. Similarly the terminals of the thermocouple I are connected to the contacts I' and I², and the 30 terminals of the thermocouple J are connected to the contacts J' and J², and the switch arms K and L simultaneously engage the contacts I' and I², respectively, during a second fraction of each revolution of the shaft N, and 35 engage the contacts J' and J², respectively, during a third fraction of each revolution of the shaft N.

The shaft N is advantageously rotated by a timing motor N', and may be an extension of the 40 shaft N², diagrammatically illustrated as the armature shaft of the motor N'. As shown the motor N' has one terminal of its energizing winding N³ directly connected to a supply conductor 3, and the second terminal connected to the cooperating supply conductor 4, through a conductor 45 5 and a normally closed switch 6.

The instrument M shown is a self-balancing potentiometer instrument, and may well be of the commercial recording potentiometer type, 50 known as the "Brown potentiometer," the general character of which is disclosed in the Harrison Patent No. 1,946,280, granted February 6, 1934. As shown the conductor 1 is connected to one terminal M² of the potentiometer slide wire resistor M'. The conductor 2 is connected to one 55 terminal of the instrument galvanometer M³. The second terminal of the latter is connected to a contact M⁴ in engagement with, and adjustable along the length of, the slide wire resistor M'. As diagrammatically illustrated, the contact M⁴ is carried by the instrument pen carriage M⁵ and the latter is adjusted along the length of the resistor M' by the rotation of a helically grooved shaft M⁶ in threaded engagement with the carriage M⁵. The shaft M⁶ is rotated as required to 60 rebalance the potentiometer, by a power actuated rebalancing, relay mechanism M⁷, operating in selective response to the deflection of the pointer of the galvanometer M³. A constant current flow 65 through the resistor M' is maintained by a suitable source of current M⁸. In the balanced condition of the measuring instrument M, as diagrammatically illustrated, the potential drop through the portion of the resistor M' between its terminal M² and the contact M⁴, is equal in

magnitude, but opposite in direction, to the voltage of the particular thermocouple then having its terminals connected to the conductors 1 and 2 through the switch mechanism KL.

If at the beginning of each period during which 5 a particular thermocouple is connected to the instrument M, the voltage of that thermocouple is greater or less than the potential drop between the terminal M² and the contact M⁴, the galvanometer M³ will cause the relay mechanism M⁷ 10 to rotate the shaft M⁶ as required to adjust the carriage M⁵ into the position in which the potential drop between M² and M⁴ is equal to said voltage.

Certain regularly recurring rebalancing operations of the relay mechanism M⁷, produce corresponding adjustments of the furnace heat regulating valve G, by means diagrammatically shown as comprising a mechanical link connection O between the instrument carriage M⁵ and a movable contact P. The latter is the primary control element or instrument resistor contact of the control circuit network, or bridge circuit, of a type of control apparatus which is in extensive commercial use, and is commonly referred to as 25 a "proportioning" system, and includes a so-called "proportioning" relay, shown herein as a reversible motor R. The latter is actuated by voltage variations, or unbalance due to adjustment of the contact P, in the bridge circuit, to adjust 30 the fuel valve G, and to simultaneously rebalance the bridge circuit by adjusting a contact Q.

As shown, said bridge circuit comprises two slide wire resistors p and q, connected in parallel between branches 7 and 8 of conductors 3 and 5, 35 respectively. The contact P engages the resistor p, and is adjusted along the length of the latter by the link O, on, and proportionally to, each adjustment movement of the carriage M⁵. The contact Q engages, and is adjusted along the length 40 of resistance q, when the motor R is in operation, through an operating connection R' between the armature of the motor R and the contact Q. Similar coaxial solenoid coils, SA and SB, each 45 connected in series with one another, and in parallel with the resistors p and q, between the conductors 7 and 8. The common junction or terminal S of the coils SA and SB, is connected by a conductor 9 to the contact P, and by a conductor 50 10 to the contact Q.

In the balanced condition of the bridge, the potential drop between the conductor 8 and the contact P is equal to the potential drop between the contact Q and conductor 7, and the current 55 flow is the same in the coil SA as in the coil SB. Any adjustment of the contact unbalances the bridge, if the latter is previously balanced. The unbalancing of the bridge makes the amount of current flow through one of the coils SA and SB, 60 greater than through the other, and thereby causes movement of the solenoid armature S', in one direction or the other, away from its normal neutral position shown. The armature S' is mechanically connected to a movable switch 65 arm T, which is shifted from the intermediate, open circuit position shown in the drawing, by movement of the armature S' out of its neutral position, into a position in which it engages one or the other of the switch contacts T' and T², 70 depending on the direction of the movement of the armature S'. Such engagement of T with T' or T², is required to permit, but as hereinafter explained, does not necessarily result in, energization of the motor R.

An adjustment of the contact P to the right, as seen in the drawing, with the bridge previously in balance, will make the current flow through the coil SB smaller than the current flow through the coil SA, and the armature S' then tilts switch T into engagement with the contact T'. Conversely, an adjustment of the contact P to the left, with the bridge, previously in balance will make the current flow through coil SB larger than the current flow through the coil SA, and the armature S' will then tilt the switch blade T into engagement with contact T'. On the assumption that contact P moves to the right in response to an increase in the thermocouple voltage measured by the instrument M, any operation of the motor R, which may occur as a result of engagement of switch blade T with contact T', will be in the direction to give a closing adjustment to the fuel valve G, through the operating connection R² between the armature of the motor R and the valve G, and to give a rebalancing adjustment of the contact Q to the left, through the operating connection R. When the unbalancing adjustment 25 of the contact P is to the left, it results in an adjustment of the switch arm T into engagement with the contact T', and the resultant operation, if any, of the motor R, is in the direction to give an opening adjustment to the valve G, and to adjust the contact Q to the right.

Operation of the motor R in the direction giving an opening adjustment of the fuel valve G results from the energizing of the motor winding R³, which must then have one terminal connected to the contact T'. Operation of the motor in the opposite direction results from the energization of motor winding R⁴, which must then have one terminal connected to the switch contact T'. The winding R³ is disconnected from the contact T' when the valve G is given its maximum permitted opening adjustment, by the opening of a limit switch R⁵; and a limit switch R⁶ is opened to disconnect winding R⁴ and contact T', when the valve attains its fully closed position. The switches R⁵ and R⁶ form part of a limit switch mechanism, which may be of any usual or suitable type, and as shown, is actuated by a connection R' to the motor armature. The switch blade T is connected to the supply conductor 3. The second terminals of the windings R³ and R⁴ are connected together, and both are connected to the conductor 5, and thereby to the conductor 4, when the switch 50 and one, at least, of two switches U and W are in their closed positions.

The switch U is moved between open and closed positions by a cam N⁴ carried by the timing motor shaft N², and the movement of the switch U is so timed relative to the movements 60 of the switch arms K and L, that the switch U is closed only during intervals in which the work bottom thermocouple I is connected through conductors 1 and 2 to the instrument M. The switch W is closed by a movement of the instrument carriage M⁶ into a high temperature position, in which it engages a lever X and tilts the latter from the full line into the dotted line position shown in the drawing. The high temperature position of the carriage M⁶, tilting the lever X into its dotted line position can occur, under 70 normal operating conditions, only when the furnace thermocouple J is connected through conductors 1 and 2 to the instrument M, since normally when full working temperatures have been attained, the minimum temperatures of the

thermocouple J will be much higher than the maximum temperature of either thermocouple H or I. By way of illustration, merely, it is noted that in the regular use of one particular furnace employed for one particular annealing 5 operation, the maximum desirable temperature of the thermocouple J is slightly in excess of 1700° F., while the maximum temperature of each of the work thermocouples H and I, is between 1300° and 1400° F. 10

The measured temperature at which carriage M⁶ will tilt the lever X, can be adjusted by varying the length of the link W' connecting the switch W to the lever X, and by adjusting the position of the lever X along the length of the grooved shaft M⁶. As diagrammatically illustrated, the length of the link W' may be varied by means of a turn buckle W² threaded to sections of the link W', which it connects. The position of the lever X may be adjusted, as diagrammatically shown, by rotation of a screw X' extending through a stationary nut X² and swivelled to a movable support X³, on which the lever X is pivotally supported. 20

As will be apparent, the operation of the motor R in the direction to give the valve G an opening adjustment, can occur only when the switch T engages contact T' and the limit switch R⁵ and switch U are each closed. Since the closure of the switch W results from the movement of the carriage M⁶ to the right into a high temperature position, the solenoid armature S' is not actuated to tilt switch blade T into contact with T', under the condition in which the switch W is in its closed position. Furthermore, the switch blade T can be in engagement with the contact T' only during an interval in which the temperature of the work thermocouple I is lower than that required to balance the bridge with the contact Q in the position corresponding 40 to the previously existing adjustment of the fuel valve G. 30

The operation of the motor R in the direction to give a closing adjustment to the valve G can occur only when the limit switch R⁶ and one, at 45 least, of the switches U and W are closed, and the switch blade T is in engagement with the contact T'. As will be apparent, the motor R may be operated to give a closing adjustment to the valve G, when the furnace temperature 50 is high enough to result in the closure of the switch W by the action of the carriage M⁶ on the lever X, and when the temperature of the thermocouple I is higher than the temperature corresponding to the previous existing adjustment 55 of the valve G and contact Q.

From what has been said, it will be apparent that the heat supply to the furnace is controlled by the temperature of the work bottom thermocouple I, except as that control is modified by 60 intermittent reductions in the rate of heat supply, made, on the attainment of a temperature by the furnace thermocouple J which has been predetermined as a desirable maximum temperature, and which results in the closure of the switch W. The range of variations in temperature of the lower work thermocouple I, in which the valve G is subject to adjustment in response to said variations, depends upon the adjustment of the apparatus. For ordinary conditions, I now 70 consider it desirable to adjust the apparatus so that, insofar as control due to the thermocouple I is concerned, the valve G will be wide open, when the temperature of the thermocouple I is not high enough to cause movement of contact P to the 75

- right of its mid position along the resistor p . Such adjustment of the apparatus is effected by so relatively proportioning and arranging the connections through which the motor R adjusts the contact Q , valve G , and limit switch R^s , that as the motor R moves the contact Q to the right into its mid position, it simultaneously adjusts the valve G into its wide open position and opens the limit switch R^s , so that motor R is then prevented from further movement in the direction to open the valve G and adjust the contact Q to the right.

The temperature of the thermocouple I which corresponds to the mid position of the contact P , may be made anything desired, within practical limits, by suitable adjustments of the apparatus, as, for example, by rotating a turn buckle O' in threaded engagement with the sections of the link O , which it connects. With the apparatus adjusted as above described, the fuel valve G will be in position to pass the maximum amount of fuel throughout the entire heating up operation, in which the temperature of the thermocouple I is increased from its initial atmospheric temperature to the temperature corresponding to the mid position of the contact P , unless, as may sometimes happen, during the final portion of the heating up operation, the temperature of the furnace thermocouple J becomes high enough to effect closure of the switch W . During the heating up operation, each closing adjustment of the valve G , effected while the thermocouple J is connected to the instrument N , will be followed by an opening adjustment of the valve G , when the thermocouple I is next connected to the instrument M .

With the substantial difference normally prevailing between the temperatures of the thermocouples I and J , the pen carriage M^s must be given an appreciable adjustment following the connection of either thermocouple to the instrument M . The initiation of control actions, during the periods in which the carriage M^s is being adjusted and its position does not correspond with the temperature of either thermocouple, may be prevented by use of provisions disclosed in said Patent No. 1,946,280, for delaying the control actions of a self-balancing potentiometer when a rebalancing operation is required.

In the drawing, p' indicates the point along the length of the resistor p , at which the latter is engaged by the contact P , when with thermocouple I connected to instrument M , the resultant rebalancing motion of the motor R will completely close the valve G . As those skilled in the art will understand, the distance between the point p' and the mid point of the resistor p determines what is sometimes called the "throttling range" of the valve G , i. e., the range of variation of the controlling temperature of the thermocouple I , required to effect adjustment of the valve G between its wide open and its fully closed positions. With the temperature of the work thermocouple I , within said range, valve G will be given an opening or closing adjustment, whenever the switch U is closed, if adjustment of the contact Q to the right or left is then necessary to rebalance the bridge circuit.

When the temperature of the thermocouple I is within its throttling range, as when lower, the closure of the switch W will result in a closing adjustment of the valve G , and the next closure of the switch U , may result in an adjustment of the valve G in either direction, or in no adjustment at all, depending on the relative positions of the

contacts Q and P , when the position of the latter correspond to the temperature of thermocouple I . It thus follows that whenever the furnace temperature is high enough to close the switch W , the rate of heat supply is jointly dependent on the temperatures of the thermocouples I and J . With a lower temperature of the thermocouple J , the rate of heat supply depends wholly on the temperature of the thermocouple I .

As will be understood by those skilled in the art, the throttling range of the valve G may be varied by varying the extent of throttling movement given the movable member of the valve G , relative to the extent of movement given the contact Q , by a given extent of movement of the motor R . Such an adjustment can be effected by mechanical adjustment provisions and in other known ways. For example, it may be accomplished by variably short circuiting a portion or portions of either of the resistors p and q , as by adjustment of the shunts q' , to vary the effective length of the resistor q , and thereby vary the potential drop per unit of length of that resistor.

In effecting control action through control parts adjusted by the potentiometer rebalancing mechanism, the instrument M as diagrammatically illustrated, is precisely similar in principle to the "Brown potentiometer," though in its ordinary form, that commercial instrument includes mechanical control parts and adjusting provisions, different in form from those diagrammatically indicated in Fig. 1. Such formal differences require no further discussion herein, however, because the "Brown potentiometer" is widely used and well-known, and also because for the purpose of the present invention, the instrument M may take the form of any one of various potentiometer and other measuring instruments in commercial use.

In referring herein and in the appended claims to the adjustment of the contacts P and Q , the adjustment of these contacts relative to their respective resistors p and q , is contemplated, and such adjustment may be effected by moving the resistors while the contacts engaging them are stationary as is done in some commercial potentiometer instruments as well as by moving the contacts while holding the resistors stationary, as is done in other commercial potentiometer instruments.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. The combination with a heater, of means including a single meter for alternately measuring the temperature of the heater and the temperature of work heated therein, a device adjustable to regulate the heat supply to the heater, and controlling means cooperating with the first mentioned means to adjust said device to increase or decrease said rate, if not already at its maximum or minimum, respectively, on and in accordance with decreases and increases in the work temper-

ature measured when the latter exceeds a predetermined temperature, and to reduce said rate, if not already at its minimum, whenever the heater temperature measured exceeds a second predetermined temperature.

2. The combination with a heater and devices respectively responsive to a temperature of the heater and to a temperature of the work heated therein, a measuring instrument including an element deflecting in accordance with the value of the quantity measured, means for connecting said devices alternately to said instrument, a bridge circuit including two resistors, a first contact engaging and adjustable along one of said resistors, a second contact engaging and adjustable along the second of said resistors, said circuit being adapted to be unbalanced and rebalanced by different relative adjustments of said contacts, a heat supply regulator, means through which said first contact is adjusted by and in accordance with the deflection of said element, a control motor adapted to adjust said second contact on and in accordance with the rotation of the motor in either direction, controlling means for said motor actuating the latter in response to unbalance in said bridge to effect a rebalancing adjustment of said second contact and to adjust said regulator, when said work temperature responsive device is connected to said instrument and when the other device is connected to said instrument and has attained a predetermined high temperature.

3. The combination with a heater and devices respectively responsive to a temperature of the heater and to a temperature of the work heated therein, a measuring instrument including an element deflecting in accordance with the value of the quantity measured, means for connecting said devices alternately to said instrument, a bridge circuit including energizing conductors and two resistors connected in parallel between said conductors, a first contact engaging and adjustable along one of said resistors, a second contact engaging and adjustable along the second of said resistors, means through which said first contact is adjusted by and in accordance with the deflection of said element, a control motor connected to and adapted to adjust said second contact on and in accordance with the movement of the motor, controlling means for said motor actuating the latter in response to variations in a relation of the potentials of the two contacts which may be interrupted by adjustment of said first contact and restored by the adjustment of said second contact effected by said motor, and a heat supply regulator adjusted by said motor.

4. The combination with a heater of a device responsive to a temperature of the heater, a device responsive to a temperature of the work heated which is normally lower than the first mentioned temperature, a temperature measuring instrument including an element deflecting in accordance with the temperature measured, means for connecting said devices to said instrument at alternate periods, a regulator adjustable to regulate the rate of heat supply to the heater, and means operative only during periods at which the work temperature is measured, for adjusting said regulator to increase or decrease the rate of heat supply to the furnace in accordance with the deflection of said element through a small range of deflection below or above a predetermined work temperature, and means operative only during periods in which the furnace temperature is being measured, and on the de-

flection of said element into a position corresponding to a predetermined temperature higher than the maximum temperature of said range, to decrease said rate of heat supply.

5. The combination with a heater and devices respectively responsive to a temperature of the heater and to a temperature of the work heated therein, of a measuring instrument including an element deflecting in accordance with the value of the quantity measured, means for connecting said devices alternately to said instrument, a control bridge circuit including a measuring contact adapted to be adjusted by and in accordance with the deflection of said element and on each adjustment to unbalance said bridge circuit, if previously balanced, and a contact adjustable to rebalance said circuit when unbalanced by the adjustment of said first contact, means responsive to unbalance of said bridge circuit, a regulator adjustable to regulate the supply of heat to the furnace, a motor adapted when energized to give a re-balancing adjustment to said second contact and to produce a corresponding adjustment of said regulator, a limit switch opened on adjustment of said regulator into its maximum heat supply position, a timing switch closed during periods in which the work temperature is measured and open during periods in which the heater temperature is measured, and a switch closed by said responsive means on unbalance in said circuit resulting from a decrease in the temperature measured, means energizing the motor for operating in the direction to re-balance said circuit and give a heat supply increasing adjustment to said regulator when said three switches are closed.

6. The combination with a furnace and devices respectively responsive to a temperature of the heater and to a temperature of the work heated therein, of a measuring instrument including an element deflecting in accordance with the value of the quantity measured, means for connecting said devices alternately to said instrument, a control bridge circuit including a measuring contact adapted to be adjusted by and in accordance with the deflection of said element and on each adjustment to unbalance said bridge circuit, if previously balanced, and a contact adjustable to rebalance said circuit when unbalanced by the adjustment of said first contact, means responsive to unbalance of said bridge circuit, a regulator adjustable to regulate the supply of heat to the furnace, a motor adapted when energized to give a re-balancing adjustment to said second contact and to produce a corresponding adjustment of said regulator, a limit switch opened on adjustment of said regulator into its maximum heat supply position, a timing switch closed during periods in which the work temperature is measured and open during periods in which the heater temperature is measured, and a switch closed by said responsive means on unbalance in said circuit resulting from a decrease in the temperature measured, means energizing the motor for operation in the direction to rebalance said circuit and give a heat supply increasing adjustment to said regulator when said three switches are closed, a limit switch opened on adjustment of said regulator into its minimum heat supply position, a switch closed by adjustment of said element into a position corresponding to a maximum desired heater temperature, and a switch closed by said responsive means on unbalance in said circuit resulting from an increase in the temperature measured, and means energizing said motor for operation in a direction opposite to the

previously mentioned direction, when the last three mentioned switches are closed.

7. The combination with a heater, a device responsive to a temperature of the heater, and a device responsive to a temperature of the work heated therein, of a measuring instrument including an element deflecting in accordance with the value of the quantity measured, means for connecting said devices alternately to said instrument, a bridge circuit, a measuring contact adapted to be adjusted by and in accordance with the deflection of said element and on each adjustment to unbalance said circuit if the latter is previously in balance, a second contact adapted to be adjusted to rebalance said circuit when unbalanced by the adjustment of said measuring contact, a motor adapted when energized to adjust said second contact and to produce a corresponding adjustment in the rate of heat supply to said heater, motor controlling means including means cooperating with the means for connecting said devices alternately to said measuring instrument to energize said motor for operation effecting a rebalancing adjustment of said second contact when the work temperature responsive device is connected to said instrument and results in an unbalancing adjustment of said measuring contact, and including means actuated by said deflecting element, when the heater temperature responsive device is connected to said instrument and the heater temperature attains a predetermined high value, to energize said motor to reduce the rate of heat supply to the furnace.
8. In controlling the operation of a batch heater in which the heater temperature and work temperature each increase through a substantial range during a batch heating operation, the method which consists in measuring the temperatures of heater and of work heated therein in

regular alternation and progressively increasing or decreasing the rate of heat supply to the heater by small increments as required to make said rate an inverse function of the work temperature measured when said temperature is within a throttling range of temperature substantially smaller than the full range of work temperature variation, said rate of heat supply being a maximum when said work temperature is below said throttling range except when said heater temperature exceeds a predetermined temperature, and reducing said rate of heat supply, if not already at its minimum whenever the heater temperature measured exceeds said predetermined temperature.

9. In controlling the operation of a batch heater in which the heater temperature and work temperature each increase through a substantial range during a batch heating operation, the method which consists in measuring the temperatures of the heater and work heated therein in regular alternation, and in progressively decreasing the rate of heat supply to the heater by small increments when the work temperature measured increases while within a predetermined throttling range of temperature, as required to make said rate an inverse function of the work temperature measured, and when the heater temperature measured has attained a predetermined value higher than the upper limit of said range, said rate of heat supply being a maximum when said work temperature is below said throttling range except when said heater temperature exceeds said predetermined value, and in increasing said rate of heat supply only at times at which the work temperature measured is below said upper limit.

ANKER E. KROGH.
